DESIGN FOR A DRESSING TABLE OR SIMILAR ARTICLE

Garnet C. Ellis, Baltimore, Md.

Application August 21, 1939, Serial No. 86,811

Term of patent 7 years

To all whom it may concern:

Be it known that I, Garnet C. Ellis, a citizen of the United States, residing at the city of Baltimore, in the State of Maryland, have invented a new, original, and ornamental Design for a Dressing Table or Similar Article, of which the following is a specification, reference being had to the accompanying drawing, forming a part thereof, wherein.

exhibiting my new design; Figure 2 is a front elevational view of the said dressing table; and Figure 3 is a side elevational view of the same, the other side of the aforesaid dressing table being substantially the same as the side shown.

I claim:

The ornamental design for a dressing table or similar article, as shown and described.

GARNET C. ELLIS.
